UNITED STATES PATENT OFFICE.

WILLIAM HAMILTON HALL, OF BRIGHTON, COUNTY OF SUSSEX, ENGLAND.

SPINNING-TOP.

SPECIFICATION forming part of Letters Patent No. 323,808, dated August 4, 1885.

Application filed July 7, 1884. (No model.) Patented in England March 19, 1884, No. 5,135; in Germany May 4, 1884, No. 30,964, and in France May 28, 1884, No. 162,421.

To all whom it may concern:

Be it known that I, WILLIAM HAMILTON HALL, a subject of the Queen of Great Britain, residing at Brighton, in the county of Sussex, 5 England, have invented new and useful Improvements in Spinning-Tops, of which the following is a specification.

The object and principle of the said invention are to enable the spinner of a top to 10 apply concurrently the force of both hands to the spinning without materially disturbing the position of the top, and at the same time to minimize the loss of power by friction in the act of spinning, so as to supply at once a 15 handy and more powerful means for the spinning of tops. In order to effect this the said invention consists of a doubled tape, connected with the spindle of the top at its doubled end, in the manner hereinafter mentioned, and 20 wound round the said spindle. The top is then spun by the two ends of the said tape being taken one in each hand and pulled in opposite directions, the said tape, when the top is spun, disconnecting itself automatically 25 from the said spindle. The tape may be connected by having two short pins fixed through the spindle, so that they project on either side thereof, the said tape being then attached at its central or doubled part to a cross-bar. The 30 said cross-bar is placed lengthwise with the spindle so that the ends of the said cross bar engage with the said projections, the said tape being then wound between such projections; or the said tape may be connected with the 35 said spindle, so as to automatically disconnect itself when the said top is spun by any other suitable means; and the said spindle may have upon it two disks, of suitable size and at a suitable distance apart, to guide and assist 40 the even winding of the said tape and the effectiveness thereof when pulled, as aforesaid, the said tape being wound between the said disks; and the said disks may each be slotted, with a slot curving gradually from 45 the periphery thereof to the said spindle in a direction corresponding with the direction in which the top revolves when spun, and the said tape or string being attached to a cross-bar, as aforesaid, may be then connected with

the said spindle by placing the ends of the 50 said cross-bar in the said slots.

In order to enable my invention to be fully understood, I will proceed to describe the same by reference to the accompanying drawings, which represent views of spinning-tops, 55 with means for spinning the same according to my improvements, and in the several figures of which similar letters represent similar or corresponding parts.

Figure 1 is an elevation of a top embodying 60 part of my invention. Fig. 2 is a plan of the same. Fig. 3 is an elevation of a modification. Fig. 4 is a plan of the same. Fig. 5 is an elevation of the tape, with its attachments. Fig. 6 is an edge view of the same. Fig. 7 is 65 an elevation of the top, with the tape wound around the spindle; and Fig. 8 is a plan of the same.

A is the top, and b is its spindle. c c are the two disks secured to said spindle at a suitable distance apart, to act as guides when the tape is wound around the spindle. d d are small pins attached to the spindle, and projecting laterally from the same. E is the tape for winding up the top. f is a cross-bar attached to the center of said tape, and g g are rings or handles attached to the ends of the tape.

In place of the pins d d, the disks c c may have slots h h, as shown in Figs. 3 and 4. 80 The tape E is doubled by bringing its ends together, and the projecting ends of the cross-bar or pin f are then placed either in the slots h of the disks c, Figs. 3 and 4, or between the disks c and against the pins d, Figs. 1 and 2. 85 The top being then turned the tape will be wound on the spindle b of the top, between the disks c, as shown in elevation at Fig. 7, and the part sectional plan at Fig. 8. The top can then be spun by pulling the ends of 90 the tape in opposite directions, as hereinbefore described.

What I claim as my invention, and desire to secure by Letters Patent, is—

1. A spinning-top the winding-spindle of 95 which is provided with retaining-disks c c, and stops, substantially as described, in combination with a winding-tape having a cross-bar

midway between its ends to engage with said stops, whereby the tape may be wound flatly on the spindle and upon itself from the cross-bar to its ends, all substantially as shown and 5 described.

2. A spinning-top the winding-spindle of which is provided with retaining-disks *c c*, having grooves *h h*, in combination with a winding-tape having a cross-bar midway be-

tween its ends to engage in said grooves, and 10 whereby the tape may be wound flatly on the spindle and upon itself from the cross-bar to its ends, all substantially as shown and described.

WM. HAMILTON HALL.
